UNITED STATES PATENT OFFICE

JOHN A. WIENER, OF LAUREL, MISSISSIPPI

FIBER-STOCK-REFINING APPARATUS

Application filed May 14, 1928. Serial No. 277,444.

This invention relates to fiber stock refining apparatus, more particularly to refining engines of the Jordan type.

The present invention constitutes an improvement over the apparatus described in my co-pending application, Serial No. 239,275, which was filed December 12th, 1927. In both inventions the stock is fed into the larger end of a refining engine similar to the usual Jordan in its construction, but in my present invention the plug, or core, is provided with a reversely tapered portion at its larger end in order to facilitate the entrance of the stock into the refining area between the core and the inner shell surface.

In my present construction, impeller blades are also secured to the larger end of the plug to serve as a pump for forcing the stock into the space provided by the reversely tapered portion of the plug, but for this purpose straight impeller blades rather than curved blades have been found more satisfactory.

It is therefore an object of this invention to provide a refining apparatus of the Jordan engine type, wherein improved means are provided for increasing the efficiency of the refining apparatus and the quality of the stock refined thereby.

Other and further important objects of this invention will be apparent from the disclosures in the specification and the accompanying drawings.

This invention (in a preferred form) is illustrated in the drawings and hereinafter more fully described.

On the drawings:

Figure 1 is a top plan view of a fiber stock refining apparatus embodying the principles of my invention;

Figure 2 is a sectional view taken on line II—II of Figure 1 with parts in elevation;

Figure 3 is an enlarged sectional view taken on line III—III of Figure 2; and

Figure 4 is an enlarged sectional view taken on line IV—IV of Figure 2.

The reference numeral 1 indicates a base or pedestal adapted to support a fiber refining apparatus of the Jordan type, indicated as a whole by the reference numeral 2. Said

refining apparatus 2 comprises a sectional casing 3 made up of an intermediate frusto-conical shaped shell 4 having secured thereto at its smaller end a passaged section 5 forming a discharge port 6 communicating with the bore of the shell 4 by means of an opening 7, and a passaged section 8 joined to the larger end of said shell 4 through a spacing ring 9. Said section 8 is formed with an enlarged intake port 91 opening into the hollow interior 10 of said section. The stock admitted into the intake port 91 passes from the interior 10 of said section 8 through a central opening 11 into the space 12 formed by the annular spacing ring 9.

A plug 13, substantially frusto-conical in shape, is mounted axially within the shell 4 upon a shaft 14 adapted to be driven through a coupling 15 and supported in bearing housings 16 and 17 from the base 1 in the usual manner. As is customary in engines of this type, means are provided for longitudinal adjustment of the plug within the frusto-conical shell, as by means of the threaded shaft 18 and wheels 19 and 20 connected with the shaft 14 as shown. The specific means of longitudinal adjustment of the core, however, forms no part of the present invention.

At the larger end of the core 13 there is formed a reduced portion 21 having a reverse taper 22 to that of the major part of the plug. There is thus provided an annular wedge-shaped space 23 between the inner surface of the shell 4 and the reduced portion 21 of the plug for facilitating the admission of stock between the refining surfaces of the plug and shell respectively.

The refining elements comprise knives 24 and 25 set in the plug 13 and along the bore of the shell 4 respectively in the customary manner. It should be noted, however, that the knives 24 positioned on the plug 13 extend along the surface of the reduced portion 21 as at 26 and are co-extensive with the length of said core.

By virtue of this construction, the portions 26 of the knives 24 act much in the same way as the runner blades of a pump to force the stock between the refining elements.

An impeller 27, comprised of radially ex-

tending straight blades 28 secured to the larger end of the plug 13 serves as the main impelling force for causing the stock to flow through the refining engine in a reverse direction to that normally taken by the stock in the usual Jordan engine. The blades 28 of said impeller 27 are substantially the width of the annular chamber 12, leaving but a small clearance between the edge of said central opening 11 and the outer edge of the blades 28. A portion of each of said blades 28 near the shaft 14 is cut away as at 29 to facilitate the flow of the stock into the annular chamber 12. The rapid rotation of the impeller blades results in the stock being thrown outwardly against the inner wall of the annular ring 9 and into the annular wedge-shaped space 23 where the stock is caught up by the revolving blade portions 22 and forced into the refining area.

20 The above described construction appears to prevent the stock from becoming bunched up before entering the refining area and furthermore, the present construction facilitates 25 the even flow of the stock through the refining engine by building up a fairly constant pressure of the stock ahead of the actual refining area. By forcing the stock under pressure through the refining engine in a direction 30 the reverse of that which would be normally effected by the centrifugal action of the rotating plug, the character of the refined fiber stock is considerably improved over the quality obtained in the usual form of Jordan 35 engine.

40 This appears to be due to the fact that the normal centrifugal action of the plug is overcome by a fairly constant greater positive pressure brought about by my novel construction of the plug, so that the fibers have a greater tendency to rub against each other in their course through the refining apparatus.

I am aware that many changes may be 45 made and numerous details of construction may be varied through a wide range without departing from the principles of this invention, and I, therefore, do not purpose limiting the patent granted hereon otherwise 50 than necessitated by the prior art.

I claim as my invention:

1. Fiber stock refining apparatus, comprising a shell having a frusto-conical shaped bore, a frusto-conical shaped plug adjustably 55 mounted in said bore and having a reversely tapered portion at its larger end and means for introducing fiber stock at the larger end of said shell for passage through said bore to the smaller end.

60 2. A fiber stock refining engine of the Jordan type, comprising a shell having a frusto-conical bore provided with knives, a frusto-conical plug also provided with knives and rotatably mounted within said bore, said plug 65 having its larger end substantially reduced

to provide an enlarged space between the plug and the shell for the introduction of stock, and impeller blades secured to said larger end of the plug to force the stock into said space.

In testimony whereof I have hereunto subscribed my name at Laurel, Jones County, Mississippi.

JOHN A. WIENER.
